Kassnar Imports, Harrisburg, Pa.

Filed May 10, 1971, Ser. No. 142,109

Term of patent 14 years

Int. Cl. D22—99

U.S. Cl. D22—9

FIG. 1 is a top plan view of a recoil pad for firearms showing my design;

FIG. 2 is a side elevational view thereof, the opposite side being the same;

FIG. 3 is a left end elevational view thereof; and

FIG. 4 is a right end elevational view thereof.

The characteristic features of my design reside in the specific configuration of the face portion of the pad as best shown in FIGS. 1 and 2.

I claim:

The ornamental design for a recoil pad for firearms, substantially as shown and described.
